LIGHTED CIGARETTE DISPENSER

Murray Kirsch, Mamaroneck, N. Y.

Application February 6, 1948, Serial No. 6,705

5 Claims. (Cl. 312—86)

1

This invention relates to lighted cigaret dispensers.

It is an object of the present invention to provide a lighted cigaret dispenser by a single operation of a lever adapted to be depressed, a cigaret will be moved outwardly into a position to be sucked upon by an air intake such as provided on an engine and wherein a heater element which has been brought into an incandescence will be engaged upon the end of the cigaret to light it and to force the cigaret toward the air outlet at the mouth end of the cigaret, whereby to engage the cigaret tightly to effect the quick lighting of the cigaret.

Another object of the present invention is to provide a construction which is simple, inexpensive to manufacture, has a single operating shaft which serves to effect plural operations when rotated by the lever, easy to install on an automobile, small and compact, has minimum parts and efficient in operation.

For a better understanding of the invention, reference may be had to the following detailed description taken in connection with the accompanying drawing, in which

Fig. 1 is a perspective view of my lighted cigaret dispenser on the steering post of an automobile;

Fig. 2 is a perspective view of the dispenser with one end broken away to show the heating element operating members and the connection of the lever with the main shaft;

Fig. 3 is a fragmentary perspective view of the opposite end of the dispenser with portions broken away to show the switch and the air valve operable by an arm on the shaft;

Fig. 4 is a transverse sectional view taken on line 4—4 of Fig. 2;

Fig. 5 is a fragmentary perspective view looking from the interior parts of the dispenser;

Fig. 6 is a fragmentary and sectional view looking in elevation upon the cigaret and after the heating element has been brought into engagement with the same to effect the lighting action, the section being taken generally on line 6—6 of Fig. 2;

Fig. 7 is a fragmentary end elevational view of the dispenser and looking upon the heating element.

Referring now to the figures, 10 represents a steering post of an automobile on which my lighted dispenser 11 is mounted by a clamp 12. The dispenser is so mounted as to provide easy access to a discharge opening 13. Cable wires 14 are extended from the same for connection

2

with a battery while small hose 15 extends from the same for connection with the air intake of the engine not shown. This hose 15 can be connected to a vacuum producing device on the automobile. For example, it can be connected into the windshield wiper hose. If desired the dispenser 11 can be mounted on dashboard 16. When it is desired to dispense a cigaret a single lever 17 is depressed and held for a second or two and is then released. Thereafter a lighted cigaret will be dropped into discharging opening 13 and may be taken therefrom by the smoker.

The dispenser comprises a body 18 which is curved inwardly to support cigaret 19 and to provide for a chamber 21. A cover 22 hinged as indicated at 23 to back 24 can be lifted to give access to the chamber 21 for the disposal of loose cigarettes therein. On the back 24 is a strip to which a spring carrier plate 26 is attached by three screws 27. On the lower end of the plate is a carrier portion 28 for supporting a cigaret. As the carrier moves outwardly of the supports 29 and 30 on which the cigarette normally rests, 25 when the carrier plate 26 has returned to its position as shown in Figure 4.

On the opposite ends of the dispenser are flanged plates 32 and 33 which serve to house the various operating parts. On the plate 32 there is pivotally connected a lever 34 having a button portion 35 which is engaged by a finger to depress the lever. The lever extends outwardly of the end plate 32 through a slot 36 in the flange of the plate. The pivot connection of the lever is at 37. The inner end of the lever engages an arm 38 and lifts the same to rock a shaft 39 extending across the back piece 24 and having a long cam 41 adapted to engage the back face of the carrier plate 26 to rock the same forwardly as the shaft is turned.

Depending from lever 34 is an operating member 42 which extends under a lever 43 pivoted on a post 44 whereby to rock the lever 43 as the member 42 rides upon a cam 45. The lever 43 will engage a spring arm 46 which bears against a heating element 47 to cause the same to be slid inwardly in the manner illustrated more clearly in Figure 6 to abut a cigaret 19 into position and force the same against an air suction opening 48 in the plate 33 whereby the lighting of the cigaret can be effected quickly. The heating element is brought into tight engagement with the cigaret end so as to be certain of the lighting action.

At the same time the shaft 39 is rotated an

arm 49 in the plate end 32 is brought upwardly to close contact terminals 51 and 52 to establish the electric circuit for the heater. These terminals are secured to the plate 32 by a screw 53.

Also within the end plate 32 is a valve arrangement 54 having a valve element 55 which is connected to the arm 49 to be lifted as the arm is raised to close the switch terminals. This operation permits air to be sucked along hose 15 and connects the dispenser with a vacuum source.

As the lever 34 is depressed shaft 39 is turned and carrier 36 is moved forwardly to force a cigaret off the supports and onto the carrier portion 28 so that the same will be carried forwardly to a position to be in line with the air suction opening 48 and with the heater element 47 so that the cigaret will be positioned to be lighted. After retaining the cigaret in this position for a second or two the lever 34 is released and the spring action of the carrier plate 26 will return the parts to their original position and at the same time the forward ends of the supports 29 and 30 will push the cigaret from the carrier portion 28 and cause the same to be dropped into a channel space 56 formed in a member 57 so that the cigaret can be supported and held until the smoker reaches into the opening 43 for it. The entire operation has taken only a few seconds and a completely lighted cigaret is quickly made available and dispensed.

It should be apparent that there has been provided a lighted cigaret dispenser which is of simple construction, neat appearance and is formed of a minimum number of parts. A single shaft serves to operate the carrier 26, switch contacts 51 and 52 and the valve arrangement 54. The heating element 47 is operated directly by the lever.

While various changes may be made in the detail construction, it shall be understood that such changes shall be within the spirit and scope of the present invention as defined by the appended claims.

What is claimed is:

1. A lighted cigaret dispenser comprising longitudinally extending members forming a chamber, end members, a carrier member vertically connected to one of the longitudinally extending members, said carrier member adapted to receive a cigaret from the chamber and move it forwardly to dispense the same, an operating member, a heating element slidably connected in one of the end members, said operating member

being connected with the carrier and the heating element to move the carrier with the cigarette forwardly and to cause the heating element to be adjusted in the end member to engage the end of the cigaret.

5 2. A lighted cigaret dispenser as defined in claim 1 and said operating member being in the form of a lever pivoted on the end member for downward pivotal movement, a lever connected to the end member for rocking movement, a spring adapted to be engaged by the lever and contacting with the heating element to urge the same into engagement with the cigaret, and a member extending between the levers to operate the lever engaging with the spring.

10 3. A lighted cigaret dispenser as defined in claim 1 and a shaft extending along the back of the dispenser and having a cam thereon for operating said carrier, said shaft being connected to the operating member to be operated by the same.

15 4. A lighted cigaret dispenser as defined in claim 1 and a shaft extending along the back of the dispenser and having a cam thereon for operating said carrier, said shaft being connected to the operating member to be operated by the same, said shaft extending into one of the end members and having an arm thereon, a switch connected to the end member to be operated by the arm, and said member having an opening in 20 communication with the valve arrangement to permit the connection of the cigaret with an air suction source.

25 5. A lighted cigaret dispenser comprising a back portion, a forward portion and end portions, said portions providing for a chamber for receiving a collection of cigarettes, a vertically-extending carrier connected to the back portion to be moved forwardly to dispense a cigaret, a bottom member having a channel space for receiving the lighted cigaret and supporting the same until taken by the smoker, said bottom member having cigarette supports extending upwardly, said carrier having a forwardly extending portion being adapted to receive and retain the cigaret upon being taken from the supports, a heater element adapted to engage with a cigarette when moved by the carrier to a position free of the supports, and said supports serving to cause the cigaret to be moved from the forward extending portion of the carrier upon the return of the carrier and to cause the cigaret to be dropped into the channel space of the bottom member.
